ELECTRIC ARC LAMP

Walter C. Mitchell, Los Angeles, Calif.

Application March 15, 1935, Serial No. 11,256

6 Claims. (CL. 176—1)

This invention relates generally to improvements in electric arc lamps of the enclosed bulb or tube type, and specifically to means for pre-heating electrodes, ionizing gaseous substances therebetween and automatically adjusting the arcing gap in accordance with the most efficient starting and operating requirements.

It is a principal object of my said invention to provide an incandescent bulb lamp, preferably of common and well known form, in which, principally for the production of the ultra-violet rays for therapeutic purposes, an electric arc may be formed and maintained, and which is adapted for use in the standard incandescent lamp socket and in connection with the usual lighting circuit.

A common form of electric mercury-vapor arc lamp in extensive use for the purpose mentioned, is known by the trade-name "Sunlamp", manufactured and distributed by the General Electric Company. Not being designed for use with standard incandescent lighting fixtures, and requiring a transformer to cut down the usual lighting circuit voltage, the "Sunlamp" can only be employed with specially designed fixtures, including a transformer built in the base of the supporting holder or stand.

It is an important object of the present contribution to the art to eliminate the transformer, and by such design as will permit use in the standard incandescent lamp socket to avoid the necessity of specially constructed fixtures and supports, thus saving expense.

Still another object is the provision in an arc lamp of adequate means for most efficiently pre-heating electrodes and ionizing gaseous substances between them for the initial formation of the arc, and the provision of thermostatic means by which, when formed, the arc is automatically adjusted as to length for the best ray-producing results.

Efficiency, particularly as it relates to the production of maximum ultra-violet radiations by the proper automatic spacing of the arcing points, simplicity, and consequent durability, resulting both in economy of manufacture and of maintenance, are other vital objects of said invention.

Other objects and corresponding advantages will be apparent to those of skill in the art from the following detailed description.

In the drawing, Fig. 1 illustrates a combined prospective and diagrammatic view of a preferred embodiment of my invention;

Fig. 2 is a similar view of a modification of the same;

Fig. 3 is a like illustration of a second modified form.

Referring to the drawing in detail, the numerals of which indicate similar parts throughout the several views, 5 designates a glass bulb substantially exhausted of air, mounted in a base, 6, of conventional form. In the bottom of bulb 5 a drop of mercury 7, adapted to be vaporized by means about to be described, is placed.

Lead wires, 8 and 9, from the usual terminals 10 are held rigidly in a glass neck 10, which is secured in the base 6, in a manner well known in the art. Filament 11 connects the ends of wires 8 and 9, said latter wire being longer and having a curved extension, 9a, at its end, permits filament 11 to be obliquely disposed relative thereto. Secured to wire 9 adjacent glass neck 10 is a thermostatic conductor 12, of laminated composite construction, comprising two strips of metal of different relative thermic expansibility, adapted to be heated by the incandescence of filament 11, and arranged so as, after the formation of the arc, to bend away under the influence of heat, from wire 8, as hereinafter more fully explained.

13 indicates an electrode preferably composed of tungsten, secured to wire 8 proximate its lower end, adapted in operation to form an arcing point with a second similar electrode 14 on the end of thermostat 12, both of which electrodes are located directly above filament 11 and designed so that there is only a small gap between them when cold.

In operation of the lamp an electric circuit is established through wire 8, filament 11 and wire 9, which immediately incandesces said filament in the manner and for reasons well known in the art. The heat generated by the incandescence of filament 11 radiates to the electrodes, heating them and also vaporizing the mercury located in the bottom of the bulb 5, thus producing necessary ionization to facilitate the formation of an arc between the electrodes. There being less resistance through the electrodes, once heated and the arc started the electric current through filament 11 ceases, and the current continues to maintain the arc.

The heat generated by the arc affects the thermostatic conductor 12 which bends away from wire 8, widening the gap between the electrodes and regulating the length of the arc. The electrode 14 will return to its initial position when cooled due to the different ratio of contraction of the elements comprising the thermostat.

It is thought that the general principles and mode of operation fully explained, the different forms in which my invention may be utilized as exemplified, for instance, in Figs. 2 and 3 of the drawing, will be quite clear to all of skill in this art, and that further details of differentiation between such illustrations need not be set forth.

It will be understood that I do not limit myself to any particular form or material of bulb or tube, nor to kind or character of materials of conductors, electrodes or their arcing points; neither do I limit my invention to any of the specific forms of filaments nor their relative arrangements with respect to the thermostatic element as illustrated in the different figures of the drawing, as it will be obvious that such invention may be embodied in other forms and arrangements with like effects.

It will be apparent that I have produced a device in which the great initial heat of the filament necessary to vaporize the mercury and heat the electrodes, which, if continued, would be destructive to the lamp, will, with proper design by those of skill in this art, be extremely brief, and the necessity of employing what is known as the poor-regulation transformer in which an initial high voltage is quickly cut down to avoid destructive effects is eliminated. When formed, the thermostatic member being properly designed, the arcing electrodes will be gradually separated to maximum space, permitting efficient operation.

What I claim and desire to secure by Letters Patent is:

1. In an electric arc lamp, a pair of terminals, a lead wire connected to each of said terminals, a resistance coil rigidly secured at opposite ends to said wires so as to form and maintain a conductor from one of said wires to the other thereof, an electrode connected to one of said wires, a movable electrode connected to the other of said wires by a bi-metal thermostat, said thermostat normally spacing said movable electrode from said first-mentioned electrode and adapted to further separate said electrodes when heated by the formation of an arc therebetween, and a substance adapted to be ionized by the heat of said resistance coil to form and maintain during all stages of relative movement of said electrode a conductor between said electrodes of less resistance than said resistance coil.

2. In an electric arc lamp, a pair of terminals, a sealed bulb, a lead wire connected to each of said terminals extending into said bulb, a resistance coil rigidly secured to opposite ends of said wires so as to form and maintain a conductor from one of said wires to the other thereof, an electrode connected to one of said wires, a movable electrode connected to the other of said wires by a bi-metal thermostat, said thermostat normally spacing said movable electrode from said first-mentioned electrode and adapted to further separate said electrodes when heated by the formation of an arc therebetween, and a substance within said bulb adapted to be ionized by heating, said resistance coil being adapted upon the passage of an electric current therethrough to simultaneously ionize said substance and heat said electrodes to provide and main-

tain a conductor across said electrodes during all stages of relative movement thereof of less resistance than that of said resistance coil.

3. In an electric arc lamp, a sealed bulb, a pair of terminals, a lead wire connected to each of said terminals extending into said bulb, said lead wires having their opposite ends inseparably connected by means of a resistance filament, an electrode carried by one of said lead wires, a bi-metal thermostat supporting a second electrode adjacent the first-mentioned electrode but adapted to maintain a gap therebetween, having its opposite end connected to the other of said wires so as to form an electricity-conductive by-pass around and of less resistance than said resistance filament upon the formation of an arc between said electrodes, said thermostat being adapted to increase the gap between said electrodes upon being heated by said arc, embodying means to limit the separation of the electrodes and thereby limit the resistance to said arc caused by such separation to a point below the resistance of said resistance filament, and means within said bulb adapted to be ionized by heat from said resistance filament to form a conductor between said electrodes.

4. In an electric arc lamp, a pair of terminals, lead wires from said terminals into a sealed bulb, an electrode connected to one of said lead wires, a second movable electrode connected to the other of said lead wires by means of a bi-metal thermostat, said thermostat being adapted to maintain a gap between said electrodes, a substance adapted to be ionized by heat to permit the formation of an arc between said electrodes, and a resistance coil inseparably connecting said lead wires of greater resistance to the flow of electricity than the electrodes and the area therebetween.

5. In an electric arc lamp, a pair of terminals, means comprising a pair of lead wires and a resistance heater-coil to connect said terminals and inseparably maintain a conductor therebetween, an electrode secured to one of said lead wires, a second electrode, a thermostat connected to the other of said lead wires to support said second electrode in a position spaced from said first electrode, said resistance heater-coil to ionize the gas between said electrodes, said thermostat being substantially unaffected by the heat of said heater-coil but movable by the heat of said arc to further separate said electrodes, said resistance heater-coil forming an electricity-conductive circuit between said lead wires of greater resistance than across said electrodes.

6. In an electric arc lamp, a pair of terminals, means comprising a pair of lead wires and a resistance heater-coil to connect said terminals and inseparably maintain a conductor therebetween, an electrode secured to one of said lead wires, a second electrode, means connected to the other of said lead wires to support said second electrode in a position spaced from said first electrode, said resistance heater-coil to ionize the gas between said electrodes whereby an arc will form between said electrodes, said resistance heater-coil forming an electricity-conductive circuit between said lead wires of greater resistance than across said electrodes.
